UNITED STATES PATENT OFFICE.

THOMAS E. PURCHASE, OF DANVILLE, PENNSYLVANIA.

GRATE FOR FURNACES.

Specification of Letters Patent No. 27,155, dated February 14, 1860.

To all whom it may concern:

Be it known that I, THOMAS E. PURCHASE, of Danville, county of Montour, in the State of Pennsylvania, have invented a new and useful Improvement in Grates for Furnaces; and I do hereby declare that the following is a full and exact description thereof, reference being had to the accompanying drawings and to the letters of reference 10 marked thereon.

My invention relates to certain improvements in the grates of puddling, or other furnaces, and has for its object the construction of the grate in such manner that the 15 fire in any particular locality may be dropped without affecting the rest.

Previous to my invention the grate of a furnace has been constructed with a series of comb-like grate bars interlocking each 20 other and so arranged as to be capable of being turned to shake up the fire or let it drop through; but in this description of grate the whole body of fire must be affected simultaneously and no portion of the fire 25 can be dropped without dropping the whole.

The nature of improvement consists in the combination of a series of comb-like grates or grate bars so arranged as to be each capable of being oscillated on its axis 30 independently of the others (as will be hereinafter fully described) in order that any desired part of the fire may be affected without affecting the rest.

In the accompanying drawings forming 35 part of this invention Figure 1 represents a front elevation of a puddling furnace in which is arranged one of my improved grates. Fig. 2 represents a vertical lateral section of the same. Fig. 3 represents a 40 skeleton perspective of the grate bars and frame. Fig. 4 represents a plan of the same. Fig. 5 represents plan and end views of one of the double "comb" bars. Fig. 6 represents bottom and end views of one of 45 the single or side bars. Fig. 7 represents a perspective view of the same. Fig. 8 is a perspective view of the turning key or wrench and Fig. 9 is a perspective view of one of the retaining caps.

50 The same parts are indicated in the different views by the same letters.

A is the body of the furnace B the air chamber, and C its door.

The double combs consist each of a bar D, 55 which is hung at each end so as to turn

freely on its axis and is formed with a series of radiating arms a, on opposite sides, each set of arms a, interlocking with those of the adjoining comb (see Fig. 4). The single or side combs (which are sometimes called 60 "hermaphrodite bars") are formed of a bar E, similar to D, and similarly hung, but having only one set of arms b, and being formed with a stop plate e. The bars D and E, are all formed with squared ends to accommodate 65 a key by which they are turned (as will be presently described).

F are retaining keys which are hollowed out to fit over the squared ends of the bars D and E and are formed with a projecting 70 feather f (see Fig. 9) which fits into a corresponding slot or spline in the front plate or door of the air chamber. By this formation and arrangement of retainer F, the bars D and E are held in the desired position. 75

G is the key for shifting or turning the grate bars and the form of which will be comprehended by reference to Fig. 8.

The operation of my improved grate, illustrated at Fig. 2, where it will be seen a part 80 of them have been so turned as to discharge the cinder while the other portion still holds up the material and fire being worked; the bars are only capable of oscillating on their axes, after the retaining keys or collars F, 85 have been extricated from their seats, so that when it is desired to drop the cinder they are collected at the most convenient part of the surface of the grate and separately from the material to be retained, when the retaining 90 keys of those bars which sustain the cinder are removed and said bars by the turning key G are shifted to drop the cinder into the air chamber (as illustrated at Fig. 2) after which the said bars are turned back 95 to their normal position and locked by the replacing of the retaining keys F. It will be seen that not only can a part of the fire be dropped without affecting the remainder which is a desideratum of vital importance 100 in the puddling furnace, but also that any locality in the body of the fire may be agitated at pleasure which is a great desideratum in all kinds of furnaces, since it often happens that to economically manage the 105 fire only certain parts should be agitated (or raked) at certain times.

I do not limit my invention to the employment of any particular number of comb grate bars, nor to the particular method of 110

holding them in position. Neither do I wish to be understood as claiming broadly the combination of comb-like grate bars; but

What I claim as my invention and desire 5 to secure by Letters Patent is—

The combination of a series of comb-like grate bars each interlocking the other and each capable of being oscillated independ-

ently of the others substantially as specified for the purposes set forth.

In testimony whereof I have hereunto set my hand and affixed my seal.

THOS. E. PURCHASE. [L.S.]
